SELECTOR SWITCH DRIVE

Gerald Deakin, New York, N. Y., and John C. Jablonowski, Jersey City, N. J., assignors to International Standard Electric Corporation, New York, N. Y., a corporation of Delaware

Application June 25, 1948, Serial No. 35,203

5 Claims. (Cl. 74—34)

1

This invention relates to new and useful improvements in catch mechanism for a combination drive and clutch which may be used to move the brush carriage of one or more selectors of an automatic telephone system.

In an application by Gerald Deakin, Serial No. 35,202, filed of even date, certain features of the catch mechanism which is the subject of this invention are disclosed but not claimed.

The brush carriage of a selector is mounted on a movable rack having two parallel toothed surfaces each of which is permanently engaged by driving pinions which drive the rack back and forth. In order to impart a reciprocating movement to the brush carriage a clutch mechanism alternately couples and de-couples constantly rotating arms to gears, each of which is permanently in mesh with a pinion. Each arm has a pin by means of which it engages a catch fastened to a gear. One arm drives the brush carriage from right to left and is disengaged from its co-operating catch by disengaging means, whereupon the other arm engages its catch and drives the carriage from left to right, this cycle being continuously repeated.

According to the present invention pin retaining means are provided at either end of each catch to prevent disengagement between a pin and a catch except by the disengaging means. The pin retaining means comprise a notch at one end of a catch for seating a pin while an arm is driving a gear and a hook at the other end of the catch for preventing the pin being disengaged from the catch if the catch should be accidentally moved in a direction opposite to the movement of the pin. The possibility of such accidental movement is particularly present during the shifting of the travel of the brush carriage from right to left or vice versa.

The features of the present invention will be disclosed in the following description in which the details of the drive and clutch, as well as the catch mechanism, will be explained so that the operation of the catch will be better understood.

In the drawings:

Fig. 1 is a top plan view;

Fig. 2 is a section along the lines 2—2 of Fig.

1; and

Fig. 2a is a plan view of a catch.

In the following description it is assumed that a main driving shaft (not shown) is to the left of the selector. If the shaft is to the right the selector parts are turned upside down and operate in the same manner.

A rack 1 carries near one end, a brush carriage

2 generally indicated at 2 provided with the usual brushes which cooperate with a terminal bank and feeder strips of a selector. The rack has a central slot 3 separating two parallel toothed driving edges 4, 5 which when engaged by pinions, about to be described, drive the rack back and forth in a horizontal plane. A guide piece 6 held by screws 7 in slot 3 has grooves on two sides through which the smooth edges of rack 1 may slide.

Toothed edge 4 of rack 1 is permanently in mesh with a driver or pinion 8 and toothed edge 5 is permanently in mesh with a driver or pinion 9. Each pinion is free to rotate on pins 10 mounted on brackets 11 held to base plate 12 by screws 13. Locking rings 14 hold the pinions on pins 10.

As best seen in Fig. 2 pinion 9 is permanently in mesh with a gear 15 and pinion 8 permanently in mesh with a similar gear 16. Gears 15 and 16 are situated one above the other to rotate freely on bushings 17, 18 surrounding a driving shaft 19 which is driven in the direction indicated by the arrow by a flexible driving gear 20. The operation of driving gear 20 is well known in the so-called rotary power driven selectors and will not be herein described.

When gear 15 is coupled to driving shaft 19 by the clutch mechanism about to be described, it will drive pinion 9 which in turn drives through toothed edge 5, rack 1 and brush carriage 2 mounted thereon from right to left. During this movement pinion 8 which is in mesh with edge 4 rotates freely about its pin 10 and drives gear 16 freely about shaft 19. After brush carriage 2 has been driven to the left terminal position of rack 1, the clutch mechanism de-couples shaft 19 from gear 15 and couples gear 16 to the shaft which drives by means of pinion 8 and edge 4, the rack back from left to right. Pinion 9 and gear 15 now rotate freely. At the completion of the left to right travel of the brush carriage the right to left movement is once again commenced as above described.

45 Shaft 19 rotates in a bushing 23 projecting from a hole in bottom plate 12. Two driving arms 24 and 25 are keyed to shaft 19 by its flat side indicated at 26. Driving arm 24 is above gear 15 and driving arm 25 below gear 16. The two driving arms and the gears are held in place on shaft 19 by means of nut 27 forcing the assembly on to shoulder 28 surrounding driving shaft 19. A spacer 21 separates gears 15, 16.

A catch 30 is fastened to the surface of gear 55 15 facing driving arm 24 and a catch 31 is fastened

to the surface of gear 16 facing driving arm 25. These catches are displaced approximately 30° with respect to one another so that there will be no lost motion between the coupling of one gear and the de-coupling of the other gear as movement of the rack is shifted from right to left or vice versa.

Fingers 32, 33 are respectively pivoted at 34, 35 to arms 24, 25. Leaf springs 36, 37 are attached by screws 38 respectively to arms 24, 25. Ends 39 of the springs rest on projections 40 of the fingers and tend to rotate each finger about its pivot in a clockwise direction. This motion is limited by stops 41 forming part of the driving arms. Near the free end of fingers 32, 33, pins 42, 43 project and are adapted to engage respectively catches 30, 31.

As shown in Fig. 1, pin 42 is engaging rear notch 49 (shown for catch 31) of catch 30. Since finger 32 rotates with arm 24 and shaft 19, gear 15 will also be rotated. Gear 15 in turn drives the rack through the pinion 9 and edge 5. When gear 15 has completed one rotation carriage 2 will have been driven all the way across the selector and portion 44 of the finger will contact top roller 45 of engaging lug 46 projecting from base 12 to which it is secured by nut 29. Lug 46 pushes finger 32 in a counterclockwise direction as it comes by, lifting pin 42 out of notch 49 in catch 30 thereby de-coupling driving arm 24 from gear 15.

While gear 15 is being driven by arm 24, finger 33 is also rotated with shaft 19 and gear 16 is rotated in a counterclockwise direction by pinion 8. Catch 31 of gear 16 will not be engaged by pin 43 until portion 50 of finger 33 engages roller 51 of lug 46 which rotates the finger sufficiently for pin 43 to engage end 47 of catch 31 and ride along edge 48 of the catch and nestle into notch 49. As finger 32 is being de-coupled by lug 46 from catch 30 and gear 16, pin 43 lodges in notch 49 of catch 31 and finger 33 commences to drive gear 16 in a clockwise direction and the brush carriage from left to right.

From Fig. 2a it is seen that catch 31 has retaining means for pin 43 at either end consisting of notch 49 and hooked end 47. Notch 49 is formed so that when pin 43 lodges in it, one side of the pin rests against the bottom of an overhanging lip 60 and the other side against a relatively sharply inclined wall 61. In this way pin 43 is held against lateral displacement and since there is no lost motion between the driving and driven parts, overstepping by the selector during hunting is eliminated.

Hooked end 47 of catch 31 prevents unwanted disengagement of the parts and possible breakage between the driving and driven parts. Such disengagement could, for example, be brought about, in the absence of end 47, if one were to move by hand the brush carriage during the period of changeover from right to left or left to right movement of the carriage after one of the driving pins, e. g. 42, had been lifted out of notch 49 of catch 30 and the other pin, e. g. 43, had not yet lodged in notch 49 of catch 31. However, wall 53 of end 47 would arrest any movement of a driving pin brought about by moving the carriage by hand. A driving pin, therefore, will always be effectively connected to its catch until lifted out by lug 46.

The alignment of gears 15, 16 so that catches 30, 31 will be in proper relationship is accomplished by first aligning two holes 54 in gear 15

with two holes 55 (only one of which is shown) in gear 16, and then rotating the top gear back one hole. The pinions may then be dropped into position and the operating fingers latched to the gears. Naturally since gears 15, 16 are moving in opposite directions holes 54, 55 will be in alignment only in one position of the gears. This is not the position shown in Fig. 1.

It will be clear from the foregoing that because of the accurate and close fit between the respective parts of the assembly back lash is eliminated and overstepping by the selector even when hunting at high speeds is virtually impossible.

15 What is claimed is:

1. In a drive for a reciprocating carriage, a driving shaft, means for driving the carriage in alternate directions, a pin rotatable with said driving shaft, and a catch movable with said driving means and in cooperative relation with said pin and having pin retaining means preventing disengagement of the pin from the catch.

2. A drive for a reciprocating carriage, comprising a driving shaft, means mounted on said driving shaft for driving the carriage in alternate directions, two pins rotated with said means, two catches, one movable with the means for driving the carriage in one direction and the other with the means for driving the carriage in the opposite direction, means for moving one pin into engagement with one catch and the other pin out of engagement with the other catch and vice versa, and two pin retaining means on each catch preventing removal of a pin from a catch by rotation in either direction when a pin is engaged to a catch.

3. The device according to claim 2, and in which said pin retaining means comprise a hook at one end of a catch and a notch at the other end.

4. The device according to claim 2, and in which said pin retaining means comprise a hook at one end of a catch having a pin arresting wall and a notch at the other end of the catch having an overhanging lip.

5. In a drive for a selector brush carriage a driving shaft, a rack carrying the brush carriage and having two toothed edges, a cooperating pinion for each edge in permanent mesh therewith, two driving arms fastened to the shaft, two operating fingers mounted on the arms, a pin projecting from each of said fingers, two gears freely rotatable around the shaft, each of said gears in permanent mesh with one of said pinions, a catch on each of said gears cooperating with the pin on each of said fingers, a hook at one end of said catches and a notch at the other end of said catches, lug means for alternately connecting and disconnecting a pin to a catch as the driving shaft rotates, whereby a finger remains connected at all times to a catch until released therefrom by said lug means.
